UNITED STATES PATENT OFFICE.

WILLIAM E. LALLEY, OF SEATTLE, WASHINGTON.

WINDOW-LOCK.

1,285,249.

Specification of Letters Patent. Patented Nov. 19, 1918.

Application filed July 29, 1918. Serial No. 247,284.

To all whom it may concern:

Be it known that I, WILLIAM E. LALLEY, a citizen of the United States, residing at Seattle, in the county of King, State of Washington, have invented certain new and useful Improvements in Window-Locks; and I do hereby declare the following to be a full, clear, and exact description of the invention, such as will enable others skilled in the art to which it appertains to make and use the same.

The invention relates to a window sash fastener, and more particularly to the class of sash locks.

The primary object of the invention is the provision of a lock of this character wherein both the upper and lower sashes of the window can be securely fastened at the inside thereof, so as to hold the sashes closed without the possibility of the opening of the window from the outside thereof, yet it is to be understood that these sashes can be locked or fastened in open position at any desirable degree for ventilating purposes, thus, it being seen that the sashes can be locked in any desired position.

Another object of the invention is the provision of a lock of this character wherein the members or latches for both the upper and lower sashes can be simultaneously operated in unison thereby eliminating the necessity of manipulating both latches independent of each other, the lock being of novel form to assure the firm and secure fastening of the window sash.

A further object of the invention is the provision of a lock of this character which is strong, simple and inexpensive to manufacture and also can be readily applied to any window of common form of construction.

With these and other objects in view, the invention consists in the features of construction, combination and arrangement of parts as will be hereinafter fully described, illustrated in the accompanying drawing, and pointed out in the claims hereunto appended.

In the accompanying drawing,—

Figure 1 is a fragmentary perspective view of a window casing and portions of the upper and lower sashes of a window with the lock constructed in accordance with the invention applied;

Fig. 2 is a vertical, longitudinal, sectional view through the lock;

Fig. 3 is a vertical transverse sectional view thereof;

Fig. 4 is a top plan view;

Fig. 5 is an edge elevation.

Similar reference characters indicate corresponding parts throughout the several views in the drawing.

Referring to the drawing in detail, A designates a window frame of the ordinary well known construction within which is slidably disposed in the usual manner, a lower sash 10 and an upper sash 11, while formed at a slight elevation above the meeting rails of these sashes in the window frame A at the side thereof is a hole 12, and likewise formed in the vertical stile of the upper sash 11 at one side thereof is a hole 13, and in these holes is adapted to engage the latches of the lock hereinafter fully described.

The lock comprises a base plate 14 which may be of any desirable shape and is preferably made from metal having formed thereon at right angles to each other opposing pairs of pivot ears 15 and 16 respectively, the ears being located preferably at the left hand end portion of the base plate 14 and swingingly mounted between the pairs of ears are the latch members 17 and 18 respectively, each being formed with a bill 19 for engagement in the hole 12 or 13 as will be apparent. The latch members are supported for swinging movement upon pivots 20 which are mounted transversely in the pivot ears.

The latch member 17 is formed with a handle lever 21 at its pivot end and extending substantially at right angles thereto, while the latch member 18 is formed with a tail piece 22 which is at substantially right angles to the member 18 and in the upper edge thereof is formed a notch or recess 23 for accommodating a hand lever 21, the notch or recess being designed to serve as a seat therefor. The hand lever 21 bridges the tail piece 22, and active upon this tail piece 22 is a leaf spring 24 which at the end thereof is suitably riveted or otherwise secured to the base plate 14 at the top face thereof. The spring 24 is designed to act upon the tail piece 22 which in its turn acts upon the hand lever 21 so as to force the latch members 17 and 18 into positive locking engagement in the holes 12 and 13 in the upper sash and window frame respectively,

so that in this manner both the lock and upper sashes will be firmly held fast in the window frame to prevent the opening thereof from without.

5 At one side of the pair of pivot ears 16 is pivotally mounted upon the base plate 14, a dog 25 which is formed with a suitable nose extension 26 and on the swinging of the dog 25 in a direction to bring the nose 10 extension 26 beneath the tail piece 22 of the latch member 18 the same will be held against unlatching and likewise the relationship of the hand lever 21 bridging the tail piece 22 will hold the latch member 17 15 against unlatching. On retrograde movement of the dog 25 the latch members 17 and 18 will be freed for the manual manipulation of the hand lever 21 to enable the unlatching of the sashes, and it will be apparent that but a single operation is 20 required for simultaneously actuating both of the latch members to bring the same to releasing position. The spring 24 active upon the latch members will simultaneously move 25 the same to latching position on releasing the hand from the hand lever 21. It will also be apparent that on closing the sashes the latch members 17 and 18 will automatically engage in the holes 12 and 13 for the 30 latching of said dashes.

The holes 12 and 13 in the window frame and upper sash are of a size to accommodate the bills 19 of the latch members 17 and 18.

It is to be understood that changes, variations and modifications may be made in the lock such as come properly within the scope of the appended claims without departing from the spirit of the invention or securing any of its advantages.

40 From the foregoing it is believed that the construction and the manner of operation of the lock will be clearly understood, and therefore a more extended explanation has been omitted.

45 What is claimed is:-

1. In a window sash lock, a base, latching members swingingly supported upon the base at substantially right angles to each other and adapted to engage an upper sash 50 and the window frame when the base is carried by a lower sash so as to lock both of said sashes, and a hand lever operative upon one of the latch members and active for moving said latch members simultaneously 55 with each other.

Copies of this patent may be obtained for five cents each, by addressing the "Commissioner of Patents, Washington, D. C."

2. In a window sash lock, a base, latching members swingingly supported upon the base at substantially right angles to each other and adapted to engage an upper sash and the window frame when the base is carried by a lower sash so as to lock both of said sashes, a hand lever operative upon one of the latch members and active for moving said latch members simultaneously with each other, and a dog coöperative with one of the latch members to positively lock both members against movement.

3. In a window sash lock, a base, latching members swingingly supported upon the base at substantially right angles to each other and adapted to engage an upper sash and the window frame when the base is carried by a lower sash so as to lock both of said sashes, a hand lever operative upon one of the latch members and active for moving said latch members simultaneously with each other, a dog coöperative with one of the latch members to positively lock both members against movement, and means co-operating with the latch members to move the same in positive locking position.

4. In a lock of the character described, a base, a pair of locking members swingingly supported upon the base at substantially at right angles to each other, a tail piece 85 formed on one of the latch members, a hand lever formed on the other latch member and bridging the tail piece, and a leaf spring active upon the tail piece for the movement of the latch members simultaneously with 90 each other into positive locking position.

5. In a lock of the character described, a base, a pair of locking members swingingly supported upon the base at substantially right angles to each other, a tail piece 95 formed on one of the latch members, a hand lever formed on the other latch member and bridging the tail piece, a leaf spring active upon the tail piece for the movement of the latch members simultaneously with each 100 other into positive locking position, and means on the base and engageable with the tail piece to hold the latch members in locked position.

In testimony whereof, I affix my signature in the presence of two witnesses.

WILLIAM E. LALLEY.
